UNITED STATES PATENT OFFICE.

JAMES DALE, OF CHICAGO, ILLINOIS.

COMBINED RULING-MACHINE AND PRINTING-PRESS.

SPECIFICATION forming part of Letters Patent No. 365,972, dated July 5, 1887.

Application filed July 22, 1886. Serial No. 208,770. (No model.)

To all whom it may concern:

Be it known that I, JAMES DALE, a citizen of the United States, residing at Chicago, in the county of Cook and State of Illinois, have 5 invented a certain new and Improved Combined Ruling-Machine and Printing-Press; and I hereby declare the following to be a full, clear, and exact description of the same.

It is my object to provide a machine upon 10 which the two operations of ruling the paper and printing upon it, steps which have hitherto each constituted a separate or disconnected job, may be performed in one continuous operation.

15 To this end my invention consists in the general construction of my improvement, and it also consists in certain details of construction and combinations of parts, all as hereinafter more fully set forth.

20 In the drawings, Figure 1 is a plan view of so much of my improved machine as is necessary to show the novel and co-operative parts and illustrate their operation; Fig. 2, a broken side elevation showing the throw-off device; 25 Fig. 3, a broken sectional view of the same, taken on the line 3 3 of Fig. 2; Fig. 4, a perspective view of a detail; Fig. 5, a section taken on the line 5 5 of Fig. 1; Fig. 6, a broken sectional view of a detail shown in Fig. 5, but 30 enlarged; Fig. 7, a perspective view of a detail shown in Fig. 1, but enlarged; and Fig. 8 a longitudinal sectional view of the entire machine.

A denotes the gage or gate of a ruling machine, B the pens and beam, and C the belt-shifter, all of common construction, and arranged to operate in the usual manner with other parts of the machine, which are old and require no further description.

40 D is a type-cylinder of peculiar construction, and E is the impression-cylinder supported to rotate directly below the cylinder D, which is supported upon a shaft, F, having its bearings in the frame of the machine and 45 carrying at one end the belt-wheel F' and the gear-wheel F'', which engages with the pinion on the shaft of the vibrator H. The ink-rollers G are supported in journal-bearings G', Fig. 4, comprising each a horizontal trough-shaped receptacle, r, on a vertical extension, r', slotted, as shown, to permit its vertical ad-

justment upon the set-screws which secure the bearings to the frame M of the machine. The cylinder D is preferably formed, as shown in Fig. 1, in cylindrical sections, adjusted together on the shaft F, whereby it may be used as a continuous cylinder or only certain separated parts thereof may be used as and for the purpose hereinafter described. This cylinder may, for the sake of the lightness, be hollow, 55 and it is provided around its surface with numerous apertures t, to serve a purpose hereinafter described. The type or other form I is adjusted in any desired position upon the form-cylinder D by means (as shown in detail 60 in Fig. 7) of screw-bolts s, inserted into the apertures t, and provided in their heads s' with, preferably, two transverse openings, s'', crossing each other, to receive adjusting-screws v, which confine and hold the form, as shown in 65 Figs. 1 and 7, and permit its ready adjustment to any required position to correspond with the ruled sheet conveyed to it from the ruling-machine.

The cylinder D is provided with a "throw-off" device of common construction in printing-presses and comprising an eccentric or cam, K, on the end of the shaft F, within an adjustable box, q, in the frame of the machine, and having an arm, p, which extends from it, 70 a lever, L, pivotally connected with the end of the arm p by means of a link, p', Fig. 1, and provided with a handle, o, and spring-pawl o' to engage with the teeth of a rack, o''.

The machine being designed, as hereinbefore 80 stated, to serve in first ruling the paper, which may be a continuous web or separate sheets, and then printing it, the last-named operation being a continuation of that first named, or vice versa, whereby both may be performed 85 continuously, the ruling and printing portions must be placed in proper juxtaposition with reference to each other, and the pressure or holding strings n must extend from the ruling device, through the printing device, between the cylinders D and E, to permit the desired service. For this purpose I prefer to employ a single frame, M, to support both the ruling and printing devices, which necessitates an arrangement, such, for example, as is 90 shown in Figs. 5 and 8, for changing the course of the endless apron or cloth N, to avoid the 95

necessity of passing it with the strings *n* between the cylinders, which would obviously interfere with the printing operation. I prefer to accomplish this by passing the apron or cloth about a cylinder, over rollers *m* and *m'* and *l* and *l'*, though the apron could be in two parts, each forming an endless apron, as indicated by the dotted lines *x* in Fig. 5, and passing, respectively, at the adjacent ends 5 around the rollers *m* and *l'*, (rendering unnecessary the rollers *m'* and *l*,) which, though not so desirable, would clear the space between the cylinders *D* and *E*. Whatever the particular juxtaposition, however, of the ruling 10 and printing devices with relation to each other, strings or tapes *n* must extend from the former between the cylinders to hold the conveyed paper and permit the continuous operation aforesaid, the roller *l* being provided 15 with the usual circumferential grooves to permit the strings *n* to be set when required to avoid type on the cylinder *D*.

The throw-off device hereinbefore described 20 serves by pressing down upon the handle *o* of the lever *L* to raise the form-cylinder *D* away from its companion cylinder *E* when it is desired to prevent the printing operation in case of mistake without stopping the machinery, or to permit the ruling device to be used alone 25 when the printing operation is not required; and to prevent the movement of the cylinder *D* farther than is necessary in throwing it "off" or "on" suitable stops *k*, and *k'*, Fig. 3, are provided to limit the movement of the 30 arm *p*.

For fastening readily and securely the blanket or tympan *O* upon the impression-cylinder, I provide the mechanism shown in Figs. 5 and 6 by recessing the cylinder longitudinally to 35 form a wedge-shaped groove, *i*, and providing sharp projections or barbs, as *h*, in the groove upon which to catch the blanket at one edge, the opposite edge, by folding the blanket around the cylinder, being fastened into the 40 groove by means of a wedge, *h'*, forced over it into the groove.

The sectional feature of the cylinder is very useful in printing the same matter on sheets of different dimensions. Thus where, for example, printed matter is desired at certain intervals—say the top and bottom of a sheet, *g*, Fig. 5—requiring one form, *I*, for the top and another for the bottom, the forms being for their purpose placed and adjusted by the device shown in Fig. 7, instead of readjusting 45

them for a sheet of different length requiring the same printed matter in corresponding or different places, an operation requiring great care and attendant difficulty, the sections of the cylinder may be readily moved toward or from each other, as required, to the desired positions, and secured in place by means of the usual bolts or set-screws inserted through the hub of each section employed.

What I claim as new, and desire to secure 60 by Letters Patent, is—

1. The combination, with a ruling-machine having strings *n*, of an impression-cylinder, *E*, and a form-cylinder, *D*, between which cylinders the strings *n* extend, substantially as described.

2. The combination, with a ruling-machine having strings *n*, of an impression-cylinder, *E*, a form-cylinder, *D*, and a throw-off, substantially as described, for adjusting the form-cylinder, the strings *n* extending between the cylinders, substantially as set forth.

3. In a combined ruling and printing machine, the combination, with the frame *M*, ruling-pen device *B*, and strings *n* of the ruling-machine, of an impression-cylinder, *E*, and a form-cylinder, *D*, one above the other on the ruling-machine crosswise of the strings *n*, which pass between the cylinders, and an apron or cloth, *N*, separated between the cylinders to leave an uncovered space between them, substantially as described.

4. In a combined ruling and printing machine, the combination, with the frame *M*, ruling-pen device *B*, and strings *n* of the ruling-machine, of a form-cylinder, *D*, provided with a throw-off, substantially as described, and an impression-cylinder, the cylinders being one above the other on the ruling-machine crosswise of the strings *n*, which pass between them, and an apron or cloth, *N*, passed over rollers *m* *m'* *l* *l'* about one cylinder, to leave an uncovered space between the cylinders, and continued beyond the same, substantially as set forth.

5. The impression-cylinder *E*, provided with means for securing the blanket or tympan in position, comprising a wedge-shaped longitudinal groove, *i*, and barbs *h*, within the groove, in combination with a wedge, *h'*, substantially as and for the purpose set forth.

JAMES DALE.

In presence of—

HENRY HUDSON,
JULIUS W. DYRENFORTH.
